PACKAGE WITH IMPROVED TEAR-TAPE

Drury R. Burton, Akron, Ohio, assignor to Wingfoot Corporation, Akron, Ohio, a corporation of Delaware

Application July 9, 1947, Serial No. 759,870

1 Claim. (Cl. 229—87)

1 This invention relates to a package provided with an improved tear-tape. The tear-tape is united to a portion of the wrapper which is defined on one, or usually both sides by perforations. The tear-tape may be releasably sealed to the wrapper over the perforations or the perforations may be filled with a plastic. The invention has particular application to wrappers of rubber hydrochloride film and like wrapping materials which have no substantial grain to facilitate tearing in a straight line.

In recent years tear-tapes have been used quite extensively for opening the protective film wrapper on cigarette packages, cigars, and the like. These tear-tapes have been used most extensively in connection with transparent wrappers of regenerated cellulose. This wrapping material tears relatively easily and has a pronounced grain which is parallel to the edges of the wrapper so that on tearing it tears in a substantially straight line parallel to the edges of the wrapper. Tear-tapes have not been used satisfactorily with films which do not tear readily, nor have they been used satisfactorily with films which do not tend to tear in a straight line. No commercial tear-tape has been developed for use with rubber hydrochloride film. Unstretched rubber hydrochloride film which is the film most widely used, does not tear easily. It is grain-less so that when torn, the tear is not straight. Therefore, the ordinary tear-tapes cannot be used satisfactorily with it. The tear-tape of this invention is designed particularly for use with such rubber hydrochloride film and can be used satisfactorily with other grain-less films.

The tear-tape of this invention is located on the outside of the wrapper and not inside as is customary with the tear-tapes used with regenerated cellulose. It is permanently united to the wrapper and this union is conveniently effected by the use of heat and pressure. The union is between only a narrow area of the tear-tape and the rubber hydrochloride wrapper, and the wrapper is perforated on one or both sides of this area. In removing the tear-tape, the area of the wrapper which is united to the tear-tape is removed with it, and if the wrapper is perforated on both sides of this area the wrapper tears through the perforations and only the small area between the perforations is removed with the tear-tape. If the tear-tape is located near one edge or end of a package it is not necessary to perforate the wrapper on that side of the tear-tape nearest the edge or end of the package, because the whole end of the wrapper may readily be removed with

the tear-tape. The portions of the tear-tape which extend outwardly from each side of the area which is united to the wrapper, overlie the perforations and prevent ready passage of moisture, dust, etc., through the perforations.

To maintain the moisture-tightness of the film in spite of the perforations, the perforations may be filled with wax or other plastic or the outer edges of the tear-tape may be united to the wrapper by wax or other suitable adhesive. A preferred material for either purpose is a micro-crystalline wax with a melting point of 130°—170° F. A satisfactory wax is Lemon Syncera Wax, melting point 140°—150° F., made by Standard 15 Oil Company in Cleveland, Ohio. In a preferred method of preparing the wrapper the perforations are formed with an instrument covered with molten wax which deposits wax in the perforations as they are formed.

20 Although the invention is applicable to the use of tear-tapes with any type of package, it is illustrated in the accompanying drawings as applied to a cigar wrapper. In the drawings:

Fig. 1 illustrates a cigar wrapped in rubber hydrochloride film and provided with a tear-tape; Fig. 2 illustrates the same with the tear-tape partially removed;

Fig. 3 is a section through Fig. 1 at the wrapper;

Fig. 4 is an enlarged plan view showing the edge of the wrapper with the tear-tape fastened to it before the wrapper is applied to the cigar;

Fig. 5 is a similar plan view showing how the tear-tape removes a portion of the wrapping film when it is stripped from the wrapped cigar or other package; and

Fig. 6 illustrates the method of perforating film and simultaneously filling the holes with plastic.

Referring to the drawings, the cigar 1 is wrapped with rubber hydrochloride film 2 in any ordinary way that a wrapper is usually applied to a cigar. The tear-tape 3 is preferably printed so as to serve the double purpose of a tear-tape and cigar band. Fig. 3 shows how the wrapper is preferably lapped at its edge and also shows that the tear-tape is narrow—of cigar-band width or narrower—its length being a little greater than the width of the wrapper. The wrapper is heat-sealed together where its edges overlap, but the outer end 5 of the tear-tape is not sealed down. It is loose so that it may easily be grasped when the cigar wrapper is to be opened.

Fig. 4 shows how the end of the cigar band 5 extends beyond the edge of the wrapper. Underneath the cigar band and spaced inwardly from

its edges the wrapper is perforated at 6 and 7 and in the area 8 between the perforations the tear-tape or cigar band 3 is sealed to the wrapper. If the tear-tape is a relatively thick band of rubber hydrochloride, such that it will not readily stretch when subjected to the tension required to tear the wrapper at the perforations, the band may easily be heat-sealed to the rubber hydrochloride wrapper. The seal may be formed by pressing the tear-tape and the wrapper together with a heated roller which is narrower than the distance between the perforations 6 and 7.

In wrapping the cigar the edge 10' of the wrapper overlaps the opposite edge of the wrapper and in the overlapped area the two portions of the wrapper are heat-sealed together to form a permanent moisture-tight bond. Thus, when the cigar wrapper is to be opened, the tear-tab 5 is lifted from the cigar so as to tear the wrapper along the perforations 6 and 7. The area 8 of the wrapper which is united to the tear-tape or band 3 is lifted from the wrapper with the tear-tape and as the tear-tape tears the wrapper at the perforations the wrapper is divided into two parts. These two parts are illustrated in Figs. 2 and 5. After cutting the wrapper in two by the tear-tape, the two parts of the wrapper on each side of the tear-tape may easily be slipped off the opposite ends of the cigar.

The perforations are advantageously filled with wax or other plastic to prevent the entrance of dust, etc., and the escape of moisture-vapor, etc. This is preferably done by perforating with an instrument coated with molten plastic. Fig. 6 shows the rubber hydrochloride wrapper 2 in which the perforations 6 are being made with an instrument 10 the pointed portions 11 of which are coated with molten Lemon Syncera Wax, 12. As each perforation is completed and the pointed instrument is removed from it, a minute droplet of wax 13 is deposited within the perforation. On cooling, this seals the opening.

This type of tear-tape may form the band for a cigar. It is sealed to the wrapper. On stripping the tear-tape from the wrapper the wrapper is cut into two parts, not as an ordinary tear-tape shears a wrapper, but by removing a narrow area of the wrapper which is defined on each side by perforations. The edges of the tear-tape which extend beyond the perforations may be removably bonded to the wrapper, if desired, to prevent air and moisture from passing in or out of the perforations.

It will be evident that if instead of placing the tear-tape at the usual cigar-band position, it had been placed very near one end of the cigar, it would not be necessary to perforate the wrapper on both sides of the tear-tape. It would only be necessary to perforate the wrapper on the side of the tape away from the end of the cigar. Then

in removing the tear-tape the wrapper would be torn along this perforation and the end of the wrapper would be slipped off the cigar with the tear-tape fastened to it.

Although the invention has been described more particularly as applied to a cigar wrapper, it is to be understood that the tear-tape may likewise be applied to wrappers enclosing other objects such as packages of cigarettes and boxes of all kinds, and even to wrappers enclosing fruits such as apples, oranges, etc. Although described more particularly as applied to a wrapper of rubber hydrochloride film, it is to be understood that the invention is not limited thereto, as a tear-tape of the type described may be used with other wrapping materials, and even with wrappers such as regenerated cellulose, although it is most advantageously applied to wrappers composed of grain-less film. The tear-tape is advantageously formed of rubber hydrochloride film or other material which may be sealed to the wrapper by the application of heat and pressure, although tear-tapes of other composition may be employed and any suitable adhesive may be used to unite the tear-tape to the wrapper.

The invention is defined in the appended claim.

What I claim is:

In combination and as a part of a package, a moistureproof wrapper and outside of the wrapper a tear-tape encircling the package, a narrow, longitudinal area of the tear-tape spaced inwardly from each edge of the tear-tape being united to a narrow area of the wrapping material, said narrow area of the wrapping material being defined on each side by a line of perforations, the perforations being covered by the outer portions of the tear-tape and being filled with plastic to prevent the passage of moisture therethrough, the perforations facilitating tearing the wrapper to remove the portion bonded to the tear-tape.

DRURY R. BURTON.
